CLAIM

I claim, the ornamental design for a dosing cup, as shown and described.

DESCRIPTION

FIG. 1 is a right, front, and top perspective view of a dosing cup, showing my design.

FIG. 2 is a left, rear, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a cross-sectional view of the dosing cup of FIG. 1, taken along section line 9-9 as depicted in FIG. 3.

1 Claim, 9 Drawing Sheets
